CLAIM

The ornamental design for a makeup tool, as shown and described.

DESCRIPTION

FIG. 1 is a perspective view of a makeup tool showing our new design;

FIG. 2 is a front elevational view of the embodiment of FIG. 1;

FIG. 3 is a rear elevational view of the embodiment of FIG. 1;

FIG. 4 is a top plan view of the embodiment of FIG. 1;

FIG. 5 is a bottom plan view of the embodiment of FIG. 1;

FIG. 6 is a right side elevational view of the embodiment of FIG. 1; and,

FIG. 7 is a left side elevational view of the embodiment of FIG. 1.

The surface hatching shown in FIGS. 1-7 is intended to delineate the surface character and contour rather than a surface pattern.

1 Claim, 3 Drawing Sheets
